UNITED STATES PATENT OFFICE.

EMIL HUGO FISCHER, OF MILWAUKEE, WISCONSIN, ASSIGNOR TO THE HEINN COMPANY, OF MILWAUKEE, WISCONSIN.

TEMPORARY OR LOOSE-LEAF BINDER.

1,282,060.

Specification of Letters Patent. Patented Oct. 22, 1918.

Application filed September 13, 1917. Serial No. 191,164.

To all whom it may concern:

Be it known that I, EMIL HUGO FISCHER, a citizen of the United States, residing at the city of Milwaukee, county of Milwaukee, 5 and State of Wisconsin, have invented certain new and useful Improvements in Temporary or Loose-Leaf Binders, of which the following is a specification.

This invention relates to improvements in 10 temporary or loose leaf binders.

The object of the invention is to provide a loose leaf binder of the pin and follower type which is simple in structure, economical to manufacture, and convenient and efficient in operation.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing forming a part of this specification, in which:

Fig. I is a plan view of my improved binder, portions of the covers being broken away.

Fig. II is an enlarged sectional detail taken on a line corresponding to line 2—2 of Fig. I.

Fig. III is an inverted view of the follower, with the base bar removed.

Fig. IV is a plan view of the base bar, showing the clutch members and spring detent mounted thereon.

In the drawing, similar reference characters refer to similar parts throughout the 40 several views, and the sectional view is taken looking in the direction of the little arrows at the ends of the section line.

Referring to the drawing, I provide a pair of binder members, designated generally by the numerals 1 and 2. For convenience, these binder members will be designated as upper and lower binder members. The binder members illustrated are provided with covers connected thereto by 50 flexible hinge members 3 in the well-known manner. Binding posts 4 are secured to the lower member.

The upper binding member comprises a base bar 5 and a channel-shaped housing 6 inverted thereon and secured by means of

tongues 7 extending through holes 8 in the ends of the base bar.

I provide a pair of clutch members 9 and 10 which, in the structure illustrated, are formed of a flat blade spring 11. This 60 spring is secured to the plate 5' on the base bar 5 by means of rivets 12. The clutch member 10 is provided with a pair of upwardly and inwardly inclined tongues 13. The base bar has slots 14 extending from 65 one edge to receive the posts, while the spring clutch members project slightly over these slots to engage the posts.

The housing is provided with slots 15 registering with the slots 14. A locking bar or 70 slide 16 is mounted in the housing and provided at one end with outwardly and downwardly inclined cam fingers 17 which engage with the tongues 13 of the clutch member 10 to disengage this clutch member. 75 The opposite end of the locking bar is bent upon itself as indicated at 18 and its end is bent inwardly and downwardly to provide an inclined cam member which projects beneath the end of the clutch member 9. 80

The locking bar 16 is provided with L-shaped slots 19 and 20 adapted to be brought into register with the slots of the binder member.

The extensions 21 and 23, and 22 and 24 85 formed by these L-shaped slots extend across and close the binder member slots when the locking bar is moved to permit the clutch members to engage and move out of the binder member slots when the locking bar 90 is shifted to release the clutch members.

A spring detent 25 is secured to one end of the base bar 5 and is provided with a keeper 26 engaging the locking bar to hold it in adjusted position. A button 27 is secured to the locking bar by means of the shank 28 which projects through the slot in the housing.

In Fig. II the locking bar is shown in position to permit the clutch members to engage. When it is desired to release the binding posts the button 27 is moved toward the right whereupon the cam portions of the slide engage beneath the tongue 13 and on the end of the clutch member 9 lifting the clutch members out of clutching relation and opening the slots in the upper binder member so that it may be moved laterally from the posts.

Having thus described my invention, what 110

2
I claim as new and desire to secure by Letters Patent is:

1. In a binder, the combination of a binder member provided with posts, a clamping member comprising a base bar and a channeled housing piece mounted thereon, said clamping member being transversely slotted to provide post openings, a clutch spring secured intermediate its ends to said bar between said post openings thereof, the ends of the spring constituting clutch members adapted to engage the posts, said spring being provided adjacent one end with a pair of upwardly projecting inclined tongues, a clutch control slide disposed in said housing and having L-shaped slots adapted to register with said post openings when the slide is in its clutch disengaging position and to close said openings when in its clutch engaging position, one end of said slide being folded upon itself providing a downwardly inclined cam coacting with one end of said clutch spring, the other end of said clutch slide having downwardly extending cam fingers struck therefrom coacting with said tongues on said clutch spring so that both clutch members are actuated by the shifting of said slide, and a spring detent coacting with said slide to hold it in its adjusted positions.
2. In a binder, the combination of a binder member provided with posts, a clamping member comprising a base bar and a channeled housing piece mounted thereon, said clamping member being transversely slotted to provide post openings, a clutch spring secured intermediate its ends to said bar between said post openings thereof, the ends of the spring constituting clutch members adapted to engage the posts, said spring being provided adjacent one end with a pair of upwardly projecting inclined tongues, and a clutch control slide disposed in said housing and having L-shaped slots adapted to register with said post openings when the slide is in its clutch disengaging position and to close said openings when in its clutch engaging position, one end of said slide being folded upon itself providing a downwardly inclined cam coacting with one end of said clutch spring, the other end of said clutch slide having downwardly extending cam fingers struck therefrom coacting with said tongues on said clutch spring so that both clutch members are actuated by the shifting of said slide, and a spring detent coacting with said slide to hold it in its adjusted positions.
3. In a binder, the combination of a binder member provided with posts, a clamping member transversely slotted to provide post openings, a clutch spring secured intermediate its ends to said clamping member between said post openings thereof, the ends of the spring constituting clutch members adapted to engage the posts, said spring being provided adjacent one end with a pair of upwardly projecting inclined tongues, and a clutch control slide disposed in said housing and having L-shaped slots adapted to register with said post openings when the slide is in its clutch disengaging position and to close said openings when in its clutch engaging position, one end of said slide being folded upon itself providing a downwardly inclined cam coacting with one end of said clutch spring, the other end of said clutch slide having downwardly extending cam fingers struck therefrom coacting with said tongues on said clutch spring so that both clutch members are actuated by the shifting of said slide.
4. In a binder, the combination of a binder member provided with posts, a clamping member comprising a base bar and a housing piece mounted thereon, said clamping member being provided with post openings, spring clutch members adapted to engage the posts, one of said clutch members being provided with an upwardly projecting tongue, and a clutch control slide disposed in said housing, one end of said slide being folded upon itself providing downwardly inclined cams coacting with one of said clutch members, the other end of said clutch slide having a downwardly extending cam finger struck therefrom coacting with said tongue on the other clutch member so that both clutch members are actuated by the shifting of said slide, and a spring detent coacting with said slide to hold it in its adjusted positions.
5. In a binder, the combination of a binder member provided with posts, a clamping member provided with post openings, spring clutch members adapted to engage the posts, one of said clutch members being provided with an upwardly projecting tongue, and a clutch control slide disposed in said housing, one end of said slide being folded upon itself providing downwardly inclined cams coacting with one of said clutch members, the other end of said clutch slide having a downwardly extending cam finger struck therefrom coacting with said tongue on the other clutch member so that both clutch members are actuated by the shifting of said slide, and a spring detent coacting with said slide to hold it in its adjusted positions.
6. In a binder, the combination of a binder member provided with posts, a clamping member provided with post openings, a clutch spring secured intermediate its ends to said clamping member between said post openings thereof, the ends of the spring constituting clutch members adapted to engage the posts, said spring being provided adjacent one end with an upwardly projecting tongue, a clutch control slide provided with downwardly inclined cams coacting with one end of said clutch spring and with said tongue on said clutch spring so that both clutch members are actuated by the shifting of said slide, and a spring detent coacting with said slide to hold it in its adjusted positions.

with said slide to hold it in its adjusted positions.

7. In a binder, the combination of a binder member provided with posts, a clamping member provided with post openings, a clutch spring secured intermediate its ends to said clamping member between said post openings thereof, the ends of the spring constituting clutch members adapted to engage the posts, said spring being provided adjacent one end with an upwardly projecting tongue, and a clutch control slide provided

with downwardly inclined cams coacting with one end of said clutch spring and with said tongue on said clutch spring so that 15 both clutch members are actuated by the shifting of said slide.

In witness whereof I have hereunto set my hand and seal in the presence of two witnesses.

EMIL HUGO FISCHER. [L. S.]
